UNITED STATES PATENT OFFICE.

ALMON B. NICHOLS, OF BURR OAK, MICHIGAN.

FISH-LINE REEL.

1,125,377.

Specification of Letters Patent.

Patented Jan. 19, 1915.

Application filed December 24, 1913. Serial No. 808,542.

To all whom it may concern:

Be it known that I, ALMON B. NICHOLS, a citizen of the United States, residing at Burr Oak, Michigan, have invented certain new and useful Improvements in Fish-Line Reels, of which the following is a specification.

This invention relates to improvements in fish-line reels.

10 The objects of this invention are: First, to provide a simple, compact and automatic reel for use in drying fish-line. Second, to provide a drying reel, in which the operating mechanism is disposed within the end 15 of the reel.

Further objects, and objects relating to details and economies of structure and operation will definitely appear from the detailed description to follow.

20 I accomplish the objects of my invention by the devices and means described in the following specification.

The invention is clearly defined and pointed out in the claim.

25 A structure which is a preferred embodiment of my invention is clearly illustrated in the accompanying drawing forming a part of this specification, in which:

Figure I is a perspective view of a reel 30 embodying my invention. Fig. II is a sectional view on the line 2—2 of Figs. I and III, showing in detail the operating mechanism for said reel. Fig. III is a sectional view on the line 3—3 of Fig. II, showing in detail the spring mechanism for operating the reel and the brake for the same.

In the drawing similar reference characters refer to similar parts throughout the several views and the sectional views are 40 taken looking in the direction of the little arrows at the ends of the section lines.

Considering the numbered parts of the drawing, 3 is the base plate to which are secured the frame members 1 and 2. Shaft 8 45 is journaled in these frame members as at 9 and carries upon it the collars 7 which are secured to said shaft by set-screws or other suitable means. The collars 7 are provided with a plurality of radiating spokes 5 which 50 support the reel consisting of the wire hoops connected by the crossbars 6. The upper ends of the spokes 5 on the end of the reel nearest the frame member 2 are bent laterally toward said frame member and the hoop 4 at that side is supported on the ends 55 of said spoke. Thus the end of the reel

overhangs the operating mechanism and there is no danger of the line becoming entangled in the driving gear.

10 is a face plate which is supported on 60 the frame member 2 by means of the posts 11.

Shaft 14 is journaled in the frame member 2 and the face plate 10 and the gear 12 is fixed on said shaft. Gear 12 is in mesh with a pinion 15 fixed on the shaft 8. Shaft 14 65 is also provided with a hub 15 to which one end of the coil spring 16 is secured as at 17. The outer end of said coil spring is secured to one of the posts 11 as at 18.

19 is a strip of spring metal secured at its 70 ends to the upper posts 11 and which is adapted to act as a brake for the spring 16 when it expands in unwinding. As the coiled spring 16 unwinds and the coil becomes packed less closely together the diameter of the coil increases until its periphery bears against the strip 19 which in this way serves as a brake and helps to limit the unwinding of the coil. A strip of spring metal provided with an inwardly turned hook 20 75 is secured at 21 to one leg of the frame member 1. This hook-shaped member is adapted to catch the spokes 5 of the reel to stop the same and hold it against turning.

From the description of the parts given 80 above, the operation of the structure should be very readily understood. When it is desired to use the reel for the first time, it will have to be wound up by hand by turning the 85 reel until sufficient tension is put upon the spring 16. The end of the fish-line that is to be spread upon the reel is connected to one of the bars 6 and the reel is released by pressing back or otherwise disengaging the 90 spring catch 20 so as to release it from the 95 spokes. The reel will then quickly wind the line upon it and the line will be exposed to the air so that it can be dried very quickly. The line may be kept upon this reel until it is next desired to use the same. When the 100 fisherman wishes to use the line he simply reels it onto his casting reel from this drying reel and the operation will automatically wind the drying reel up so that it is ready for use when next desired to dry the 105 line.

I am aware that the particular embodiment which I have here set forth is susceptible of considerable variation without departing from the spirit of my invention, 110 and, therefore, I do not wish to be restricted to the same. However, I have found that

this form is to be preferred and, therefore, I desire to claim the same specifically as well as broadly as appears from the appended claim.

Having thus described my invention, what I claim as new and desire to secure by Letters Patent, is:

In a device of the type described, the combination of frame members, a shaft journaled thereon, a pair of collars on said shaft, a reel carried by said shaft and comprising a plurality of wires having a portion extending radially from one of said collars, a portion extending parallel to said shaft, said portion being bent back upon itself for a distance and a portion extending in a direction parallel to the first named portion

and radial to the second collar, and secured thereto, hoop members carried by said wires at the ends of the portions thereof which lie 20 parallel to the shaft, a pinion carried on said shaft, and spring-operated means disposed in the inclosure formed within the reel in mesh with said pinion for driving said shaft, all coacting substantially as de- 25 scribed for the purpose specified.

In witness whereof, I have hereunto set my hand and seal in the presence of two witnesses.

ALMON B. NICHOLS. [L.S.]
